CALIFORNIA.

OUTLET-BOX FOR ELECTRIC FIXTURES.

935,097.

Specification of Letters Patent. Patented Sept. 28, 1909.

Application filed June 11, 1908. Serial No. 437,962.

To all whom it may concern:

Be it known that we, OSCAR F. ERICKSON and RICHARD H. BRADSHAW, citizens of the United States, residing, respectively, at 5 Berkeley, in the county of Alameda, and Oakland, in the county of Alameda, and State of California, have invented new and useful Improvements in Outlet-Boxes for Electric Fixtures, of which the following is

10 a specification.

The present invention relates to an improved electric outlet box. Heretofore it has been a common practice to secure fixtures for electric lights direct to the lath and plaster in buildings. The objection to this construction is that, by continuous use, the screws which secure the crowfoot or other fixture to the lath and plaster become loose, and the plaster also works out or breaks off, 15 the fixture then having to be repaired.

20 The object of the present invention is to provide a construction which will obviate this objection, so that the fixture will remain firmly and rigidly in place for an indefinite period without further attention.

25 In the accompanying drawing, Figure 1 is a broken front view of our improved outlet box; Fig. 2 is a vertical sectional view of the same, showing a crowfoot secured thereon; Fig. 3 is a front view of a face plate; Fig. 4 is a view similar to Fig. 2 showing a face plate and socket supported on the outlet box; Fig. 5 is a front view of a special form 30 of crowfoot used with our invention.

35 Referring to the drawing, 1 indicates a base, adapted to be secured by screws 2 through three countersunk screw holes to the joist 3 or other rough work of the building, so as to lie flat against said joist. Said base 40 is formed in the center with an elongated aperture 4, through which can pass the electric conducting wires and their insulation. At right angles to the slot 4 said base is formed with depressed or recessed portions 45 5, the material within which is connected with the main part of the base by comparatively thin connections, so that either of said depressed portions may be easily knocked out by the blow of a hammer, leaving one, or two, lateral enlargements of the slot 4, when it is desired to pass three, or four, electric wires, with their insulation, through the center of said base, instead of two only, this being done when it is desired to take 50 off two or more branch circuits instead of

one. In any case the slot is of such limited size that the electric wires with their insulations completely fill the slot, thus reducing the danger of combustion arising from imperfect electric connections within the box. 60 Said base is formed with a circular wall 6, and, formed upon said base within said wall, and intermediate between the three countersunk holes, are bosses 7 rising not quite as high as the top of the wall. These bosses 65 are provided, so that by means of deep screw holes 8 therein, there may be firmly secured in place a crowfoot 9, which, in general, is similar to those already in use, having a central apertured portion 10 adapted to register 70 with the aperture 4 in the base, and having also feet 11, each foot being formed with a countersunk hole 12 to receive the head of a screw by which the foot is secured to one of said bosses. 75

The outlet box is secured upon the joist or other rough work, before applying the lath and plaster, and is of such depth, that, when they are applied, the plaster is substantially flush with the upper edge of the wall 6 of 80 the outlet box. A crowfoot, such as is at present used for this class of work, may then be secured to the outlet box, by screwing the same thereupon in precisely the same manner as it has heretofore been screwed to the lath and plaster itself. In other words, the box is so constructed and secured upon the rough work, that any standard crowfoot can be secured upon the box instead of upon the lath and plaster. However, we prefer to use 85 a form of crowfoot, which may be secured more rapidly and easily than the ordinary crowfoot, each foot thereof being formed with a transverse passage 13, connecting a side of the foot with the countersunk screw 90 hole 12 therein, these passages being all formed on the same side of the feet, preferably on the right hand side. Thereby the time required for securing the crowfoot in position is greatly reduced, for, the screws 95 being already partly screwed into their screw holes in the bosses, it is only necessary to place the crowfoot slightly to the left, angularly, of its proper position, and then give the same a slight turn to the right, and then the shanks of the screws will pass into the passages 13 in the feet, so that the heads of 100 said screws will be immediately over the counter-sunk holes 12, and then, on screwing down the screws, the crowfoot is secured in 105 110

place. This can be done in less than one-half the time required to screw the screws through their entire length. The fixture is then secured to the crowfoot in the usual manner.

5 In cases where it is desired to use snap switches, and other fixtures not requiring a crowfoot we provide a special form of face plate 15, formed with countersunk sockets 10 16 for screw heads, which sockets are in the proper relative positions, so that screws passed through said sockets can be screwed into the screw holes in the box in precisely the same manner as the crowfoot is secured 15 thereto. Said face plate 15 is also formed with the wire holes 17 and with the screw holes 18, so that it can be secured to any standard socket, switch, or rosette. By giving the face plate the same finish as the 20 fixtures themselves, its use improves the general appearance of the fixture.

An important feature of this invention is that the back and wall of the base are formed in a single piece having no opening, either in 25 the back or in the wall, except those for the screws 2 and for the wires and their insulation, thus providing an entirely metallic casting completely surrounding all the joints connecting the fixture to the line, whereby

the danger of combustion being started by 30 defective connections is reduced to a minimum.

We claim:

In combination with a backing for lath and plaster, and lath and plaster secured thereon, an outlet box having a base and a cylindrical wall formed integral therewith, said base being secured upon the front wall of said backing and the cylindrical wall having its front edge substantially flush with 40 the surface of the plaster, said base having a central aperture, and the backing having an aperture registering with the central aperture in the base, said base and wall having also formed integral thereon bosses with 45 screw holes therein, and a crowfoot having its feet secured upon said bosses, said feet being substantially flush with the plaster of the wall, substantially as described.

In testimony whereof we have hereunto 50 set our hands in the presence of two subscribing witnesses.

OSCAR F. ERICKSON.
RICHARD H. BRADSHAW.
